BLOWPIPE APPARATUS

Stanley B. Kirk, New Rochelle, N. Y., and Wilgot J. Jacobsson, Elizabeth, N. J., assignors, by mesne assignments, to Union Carbide and Carbon Corporation, a corporation of New York

Application October 28, 1933, Serial No. 695,606

17 Claims. (Cl. 158—27.4)

This invention relates to blowpipes for welding and cutting and like operations where a heating flame may be employed alone or in combination with an oxygen stream for severing or removing surface metal.

Heretofore air, oxygen and a fuel gas have been used in blowpipes to produce combustible mixtures. In such blowpipes no means were provided to quickly obtain or to obtain with precision, the most suitable proportions of the above components of the combustible mixture for the work to be performed. The mixtures that were produced may not only be unsuitable for the production of the best grade of work but the mixtures may also be wasteful in the consumption of the gases, particularly the fuel gas.

In such blowpipes, once the approximate proportions of the gases in the combustible mixture were obtained by manipulating two or more valves, the flame at the main nozzle was allowed to burn during the short intervals of time while the flame was not being used and further contributed to the waste of the gases.

Among the objects of the invention are: To provide improvements in blowpipe constructions of this character whereby greater efficiency in operation may be attained with greater economy in consumption of fuel gas than has heretofore been possible with blowpipes; to provide a dependable means for quickly obtaining a combustible mixture containing accurate proportions of air, oxygen and a fuel gas, and to provide a single operative means for controlling the components of said mixture; to provide an improved construction and arrangement of parts in such blowpipes whereby the gases which produce the flame will be expended substantially only while the flames are performing useful heating operations and whereby the flames may be instantly lighted and extinguished at the beginning and end, respectively, of each operation to thereby economize on the expenditure of gases without the additional expenditure of time in readjusting the gas control valves; to provide an improved arrangement of the operating control mechanism such that all operating control movements may be conveniently effected by the hand of the operator by which he supports the blowpipe; to prevent the continued burning of the heating flame after the blowpipe is dropped or otherwise released by the operator's hand; and to otherwise provide an improved, compact, and rugged blowpipe construction.

Other objects and novel features of the inven-

tion will appear from the following specification taken with the accompanying drawings, in which,

Fig. I is a view in side elevation of a blowpipe constructed in accordance with this invention;

Fig. II is a top plan view of the blowpipe handle on an enlarged scale as compared with Fig. I and in which the stem of the blowpipe is broken away and the handle casing is sectioned;

Fig. III is a bottom plan view of the blowpipe handle with the stem broken away and on the same scale as Fig. I;

Fig. IV is a view in longitudinal section on the line IV—IV in Fig. II;

Fig. V is a cross sectional view on line V—V in Fig. IV;

Fig. VI is a view in longitudinal horizontal section on line VI—VI in Fig. IV;

Fig. VII is a cross sectional view on line VII—VII in Fig. IV;

Fig. VIII is an enlarged cross sectional view of the pilot light control valves shown at the left in Fig. IV;

Fig. IX is a detail view of the injector nozzle removed from the blowpipe, and shown in longitudinal section and on an enlarged scale compared with Fig. IV;

Fig. X is a cross sectional view on line X—X in Fig. IX;

Fig. XI is a fragmentary view in side elevation of the blowpipe head and on an enlarged scale compared with Fig. I;

Fig. XII is a cross sectional view on line XII—XII in Fig. XI;

Fig. XIII is a schematic view illustrative of the various passages of the apparatus in their relation to each other and to the various control valves associated therewith as shown in Figs. I to XII; and

Fig. XIV is a schematic view of a modification of the blowpipe disclosed in Figs. I to XIII.

Most of the principles involved in this invention are applicable to welding and cutting blowpipes, or the like. However, the blowpipe shown herein Figs. I to XIII for illustrating the invention is a cutting blowpipe designed particularly for deseaming purposes. The blowpipe may comprise a handle H having blocks B, B', one secured in each end thereof to form supports for the tubes passing therethrough and to form valve bodies for the valves which control the passage of gases through the tubes to the head H^e of the blowpipe. The rear valve block B has connections for air, oxygen and a fuel gas, which gases are mixed in a mixer M built in the rear block B. The flow of the fuel gas and the oxygen for

heating purposes to the mixer M is controlled by valves V^a and V^c respectively. Intermediate the mixer M and the control valves V^a and V^c, a shut-off valve is inserted in each of the gas lines which may be operated by a lever L. The lever L and the valves it operates are herein termed a "gas saver" S. The lever L may be gripped by the hand of the operator while it is holding the handle H to admit the components of the combustible mixture to the mixer M from which the mixture is discharged through a tube in the stem S^t which connects the handle H to the blowpipe head H^e to which a main burner nozzle N is attached. The mixture when discharged from the nozzle N may be ignited by a pilot light burner P supplied with fuel gas through valves located in the forward valve block B' on the handle H. When the blowpipe is used for cutting purposes the cutting oxygen is controlled by a valve knob C positioned on the handle opposite to the gas saver lever L. The gas saver lever L, the pilot light valves and the cutting oxygen valve knob C are so arranged on the handle H that they can all be operated by the members of the same hand which grasps the blowpipe handle H.

As shown in detail in Figs. II, IV and VII, the oxygen may be supplied to the blowpipe through a hose nipple O which is connected to the cutting oxygen valve chamber 20 in the rear valve block B by a connecting nipple 21 screwed into the end of the chamber. The oxygen for forming the heating flame is conducted from the cutting valve chamber 20 through a transverse passage 22 in the rear valve block B, as shown in Fig. VII. The head 22a of the valve V^c is located in the passage 22 for controlling the flow of the heating oxygen to the mixer M. Upon opening the heating oxygen valve V^c, the oxygen passes from its inlet chamber 22 to the outlet chamber 23 of the valve and through a passage 24 in the rear valve body B. The passage 24 is connected to a tube 25 which extends through the handle H and the forward block B' in the handle to a cavity 26 in the blowpipe head H^e. A return tube 25a connects the cavity 26 in the blowpipe head to a passage 27 in the rear valve body B which leads to the inlet chamber 28 of the oxygen valve 29 of the gas saver S. Upon opening the oxygen valve 29 of the gas saver S, the heating oxygen may pass through the valve seat 30 to a longitudinal passage 31 in the valve body B and then to a transverse passage 32 to the mixer M, as shown in Fig. V. A removable mixer nozzle 33 is screwed into the bore 34 and a groove 35 is cut around the nozzle to provide a chamber 36 to receive the heating oxygen. A transverse passage 37 in the nozzle 33 extends from the chamber 36 and intersects a longitudinal central passage 38 in the nozzle. The central passage 38 conducts the heating oxygen to the mixing point at the end of the nozzle 33. As will be hereinafter described, air and fuel gas are admitted to an annular chamber 39 around the end of the nozzle 33 in the mixer bore 34. The mixer M, including the nozzle 33 is so constructed that upon discharging oxygen at a suitable velocity through the central passage 38 a sub-atmospheric pressure is created at the end of the nozzle 33. The reduced pressure tends to draw air and a fuel gas from the chamber 39 around the end of the nozzle and draw these gases into the oxygen stream.

The fuel gas is supplied to the rear valve body B through a hose nipple A which is connected to the inlet 40 of the fuel gas control valve body 41

having an outlet connection which is screwed into a bore 42 in the rear valve body B. The head 41a of the fuel gas valve V^a controls the passage of the fuel gas to the bore 42. A passage 43 having a transverse and a longitudinal bore formed in block B connects the bore 42 to the inlet chamber 44 of the fuel gas valve 45 of the saver S. Upon opening the fuel gas valve 45 of the gas saver, the fuel gas passes through a metering plug 46 which is removably secured in the outlet of the valve 45. The plug 46 is provided with an orifice 47 to limit the flow of fuel gas to a transverse passage 48 leading to the subatmospheric chamber 39 formed in the mixer bore 34 around the end of the mixer nozzle 33. 15

As shown in Figs. IV and IX, air is supplied to the mixing point at the end of the nozzle 33 through an opening 49 in a cap or housing 50 attached to the end of the mixer nozzle. A flap valve 51 made of resilient material is provided in the cap 50 to prevent the backward flow of the gases and permit the inward flow of air through the cap 50. A partition 50a is formed in the cap 50. It divides the cap into an inlet chamber 50b and an outlet chamber 50c for the flap valve 51. 25 A pair of passages 50d are formed in the partition 50a to permit the flow of air from the inlet chamber 50b to the outlet chamber 50c. A rivet 51a secures one end of the flap valve 51 to the outlet side of the partition 50a so that the other end 30 of the valve 51 is normally resiliently held over the passages 50d in the partition 50a, but is adapted to be moved away from the passages by a differential of pressure between the atmospheric pressure in the inlet chamber 50b and a 35 lower pressure in outlet chamber 50c, and permit the entrance of air through the passages 50d. The outlet 50c communicates with longitudinal passages or bores 54 in the mixer nozzle 33. The air passages 54 extend through the nozzle 33 to 40 the chamber 39 at the end of the nozzle.

The orifice 47 in the metering plug 46 is made of such a size for the fuel gas pressure used that the flow of fuel gas through the orifice will be so limited that the oxygen jet discharged through the passage 38 in the mixer nozzle 33 will be able to maintain a subatmospheric pressure in the chamber 39 at the end of the nozzle and thereby provide the necessary differential in pressure between the chamber 39 and the atmosphere to 50 draw air through the air opening 49 and the flap valve 51 and into the chamber 39. Metering plugs 46 having different size orifices 47 may be interchanged one with another to vary the proportion of air and fuel gas drawn into the combustible mixture. 55

When the oxygen and fuel gas valves 29 and 45 in the gas saver S are opened by a mechanism to be hereinafter described, the oxygen flows through the central passage 38 in the mixer nozzle 33 and draws in the fuel gas and air from the chamber 39 at the end of the nozzle 33 and mixes with these gases in the mixer throat 55 which is connected by an expansion chamber 56 to a tube 57 leading from the forward end of the handle H to a distributing chamber 58 in the head H^e of the blowpipe. The main burner nozzle N is connected to the head H^e of the blowpipe by means of a nozzle nut 59. The mixture is discharged from the distributing chamber 58 through the nozzle N in the usual manner and ignited at the end of the nozzle to provide the heating flame.

As shown in Fig. VII, the gas saver valves 29 and 45 are of the diaphragm type. They are 75

secured into cavities 61 in the rear valve body B by means of hollow nuts 62 which are screwed into the cavities 61. The nuts 62 clamp the diaphragm valves 29 and 45 between the ends of the nuts 62 and the bottoms of the cavities 61. The diaphragm valves 29 and 45 are normally retained on their seats 30 by means of springs 63 compressed between the outer end of the hollow nuts 62 and a shoulder 64 on the valve stems 65 of each of the diaphragm valves 29 and 45. Each of the valve stems 65 is attached at one end to its corresponding valve and the other end of each stem extends through its corresponding hollow nut 62. The gas saver valves 29 and 45 are operated by means of the single lever L which is pivoted on a pin 66 mounted in ears 67 on the valve body B. The outer end of each valve stem 65 is provided with a neck 68. The rear arm 69 of the gas saver lever L fits around the necks 68 and is adapted to contact with the stem heads 70 at the outer end of the necks 68 to operate the valves 29 and 45 in opposition to the springs 63. The neck 68 of the stem 65 of the oxygen valve 29 is shorter than the neck 68 of the fuel gas valve 45 and the head 70 of the stem 65 of the oxygen valve 29 is thereby placed nearer to the rear arm 69 of the gas saver lever L than the head 70 of the stem 65 of the fuel gas valve 45. Consequently, when the forward arm 72 of the gas saver lever L is drawn toward the handle H the oxygen valve 29 is caused to be opened before and closed after the fuel gas valve 45. This construction of the gas saver S turns the oxygen on before the fuel gas is turned on. The advanced opening of the oxygen valve 29 produces a sub-atmospheric pressure in the chamber 39 before or at the time the fuel gas reaches the chamber and the delayed closing of the oxygen valve continues the subatmospheric pressure after the fuel gas valve 45 has closed and thereby prevents the fuel gas from backing up into either the oxygen passage 38 or passing through the air opening 49 with the attendant danger or annoyance to the operator. The cap valve 51 is also provided to prevent the backward flow of gases through the air inlet 49 and affords protection against flames being discharged through the air opening 49, in the case of a backfire.

A pilot light burner P is provided to ignite the combustible mixture discharged from the nozzle N. As shown in Figs. VI and VII, the fuel gas for the pilot light burner P is supplied from the inlet chamber 44 of the fuel gas valve of the gas saver S through a longitudinal passage 73 in the rear valve block B. The passage 73 in the rear valve block B is connected to a passage 74 in the forward block B' on the handle H by means of a tube 75 extending between the blocks B, B'. As shown in Fig. VIII, the forward block B' is provided with valves for controlling the flow of fuel gas to the pilot burner P. A regulating valve 76 is placed in the passage 74 in the block B'. The regulating valve 76 may be operated to obtain a reduced idling flame by inserting a screw driver blade in a slot 77 cut in the valve operating head 78 attached to the threaded valve stem 79. A resilient packing ring 80 is inserted between the head 78 and the valve block B'. The ring 80 is adapted to form a seal around the stem 79 and to maintain the valve 76 in the position it may be set.

A by-pass passage 81 around the idling flame regulating valve 76 is formed in the block B' to provide a momentary supply of additional fuel gas to the pilot light burner P. The additional fuel

gas is used to increase the length of the pilot idling flame and ignite the mixture discharged at the end of the nozzle N. A by-pass valve 82 for turning on and off the additional flow of fuel gas to the pilot light burner P is inserted in the by-pass. The by-pass valve 82 is retained in the forward block B' by a plug 83 screwed into a counterbore 84 in the block. The plug 83 is provided with a central bore 85 extending therethrough. The inner end of the central bore 85 communicates with the inlet passage 74 in the block B'. A series of radial openings 86 connect the central bore 85 in the plug 83 to the by-pass passage 81. A recess is formed around the central bore 85 at its inner end and a valve seat 87 is retained in the recess between the inner end of the plug 83 and a shoulder 88 in the bottom of the counterbore 84. A valve stem 89 unitary with the valve 82 extends through the central bore 85 in the plug 83. A thumb button 90 is screwed to the outer end of the valve stem 89. The plug 83 is provided with a counterbore 91 into which packing and a packing washer 92 is fitted around the valve stem 89. A spring 93 encircles the valve stem 89 within the counterbore 91 of the plug 83 and is compressed between the packing washer 92 and the thumb button 90 to normally retain the valve 82 on its seat 87. A tube 94 is connected with the outlet 95 of the pilot valves 76 and 82 in the forward valve block B'. The tube 94 conducts the fuel gas to a bracket 96 supported by the combustible mixture tube 57 at the head end of the blowpipe. The bracket 96 is secured to the combustible mixture tube 57 by clamp screws 97, as shown in Figs. I and XI.

A bore 98 extends through the bracket 96 and is connected with the fuel gas pipe 94 attached to the bracket. A burner nozzle 99 is threaded into the bore 98 in the bracket. A cylindrical shield 100 surrounds the pilot light burner nozzle 99 and is threaded to the nipple 101 around the bore in the bracket 96.

A series of air openings 102 are provided opposite the base of the pilot light burner nozzle 99 and a series of openings 103 are also provided in the burner nozzle opposite openings 102 in the shield 100 to allow air to be drawn into the central bore 104 in the nozzle and be mixed with the fuel gas.

When the blowpipe is used for cutting or de-seaming purposes, the cutting oxygen is supplied from the inlet 105 of the cutting oxygen valve chamber 20. The flow of cutting oxygen from the inlet 105 to the outlet 106 of the valve chamber 20 is controlled by a cutting oxygen valve 107. A seat 108 for the cutting oxygen valve 107 is screwed into the outlet side 106 of the cutting oxygen valve chamber 20. The seat 108 is maintained in place by means of the locking ring 109 screwed into the outlet chamber 106 against the valve seat 108. The bore of the outlet chamber 106 is closed by a valve stem bushing 110 screwed into the end of the chamber. The bushing 110 is provided with a central bore 111 into which a valve stem 112 is inserted to actuate the cutting oxygen valve 107. A gland nut 113 surrounds the outer end of the valve stem 112 and is screwed to the end of the bushing 110. Packing 114 is compressed around the stem 112 by the nut 113. The cutting oxygen valve 107 is normally retained upon its seat 108 by a spring 115 which is compressed between the nipple 21 and a socket 116 which centers the valve 107 in the valve chamber 20. The cutting oxygen valve 107 may be operated by means of a lever 117 having the exten-

- nally extending knob C attached thereto. The lever 117 is pivoted on a pin 118 in the forward end of a block 119 in the blowpipe handle H. The lever 117 actuates a plunger 120 which is slidably supported in the block 119. The plunger 120 actuates the valve stem 112 and the cutting oxygen valve 107. The longitudinal axes of the plunger 120 and the valve stem 112 are arranged substantially parallel to each other. The axis of the plunger 20 is offset from the axis of the valve stem 112 in the direction of the axis of the handle H in order to increase the length of the short arm 121 of the lever 117 and thereby give greater movement to the valve 107.
- 15 Upon pressing the cutting oxygen valve knob C, the oxygen passes through the valve seat 108 and into the outlet 106 of the valve chamber 20. A transverse bore 122 conducts the cutting oxygen from the valve outlet 106 to a longitudinal bore 123 in the valve body B to which a tube 124 is connected for conducting the oxygen to a cavity 125 in the blowpipe head H'. The nozzle N is provided with the usual central bore for conducting the cutting oxygen from the cavity 125 to the end 25 of the nozzle N where it is discharged for use in cutting metal or the like.
- 20 A modification of the invention disclosed in Figs. I to XIII is shown diagrammatically in Fig. XIV. The blowpipe disclosed in Fig. XIV is adapted particularly for welding metals or the like. As shown in Fig. XIV, the fuel gas is admitted to the blowpipe under sufficient pressure to aspirate the air and oxygen into the mixer M'. The fuel gas is admitted through the nipple 35 A' to the fuel gas control valve V^a. A conduit 126 connects the outlet from the fuel gas control valve V^a, to the inlet of the fuel gas valve 127 of the gas saver S'. A long conduit 128 connects the outlet of the fuel gas valve 127 of the gas saver S' to the mixer M' shown in cross section. The fuel gas conduit 128 is connected to the central passage 130 in the removable mixer nozzle 131 which is screwed into the bore 132 of the mixer M'.
- 25 40 45 Oxygen under a suitable pressure is supplied to the blowpipe through a nipple O'. The oxygen is controlled by a valve V^o, the outlet of which is connected to the inlet of an oxygen valve 133 of the gas saver S' by a conduit 134. A metering plug 135, similar to the plug 46 used in the other modification, is placed in the outlet of the oxygen valve 133 of the gas saver S' and the outlet from this plug 135 is connected to an annular chamber 137 surrounding the end of the mixer nozzle 131, by a conduit 138 extending between the chamber 137 and the plug 135. In this modification the plug 135 in the oxygen conduit 138 performs the same function as the plug 46 in the fuel gas conduit of the other modification. An air passage 139 is formed in the mixer nozzle 131. It extends through the nozzle 131 and connects the chamber 137 at the inner end of the nozzle with the air at the outer end of the nozzle. The chamber 137 at the inner end of the nozzle 131 is connected to the mixer throat 140 into which the fuel gas may be discharged from the passage 130 in the mixer nozzle 131 with sufficient velocity to create a subatmospheric pressure in the chamber 137 at the end of the nozzle 131. Air is drawn through the air passage 139 into the chamber 137 and mixed with the oxygen entering the chamber. The mixture of air and oxygen is drawn from the chamber 137 into the mixer throat 140 and is mixed with the fuel gas to form a combustible mixture. The mixer throat 140 is

connected to the main burner nozzle N' in the blowpipe head by a mixture tube 141.

A pilot light burner P' may be supplied with a fuel gas through a conduit 142 leading from the inlet of the fuel gas valve 127 of the gas saver S' to the burner P'. The idling flame may be controlled by a throttle valve 143. The pilot flame may be increased in length to light the mixture by operating a bypass valve 145, both of the valves being located in the conduit 142 leading to the burner P' and adapted to function in a manner similar to the pilot control valves shown in Fig. VIII.

The arrangement of the operating parts in both of the modifications are similar except, of course, in the case of the welding blowpipe, the cutting oxygen valve is omitted.

In the operation of the blowpipe shown in Figs. I to XIII, the blowpipe is connected to suitable sources of gas supply with all of its valves closed. The fuel gas control valve V^a is fully opened. The throttle valve 76 for controlling the pilot light idling flame is adjusted and the idling flame is lighted at the pilot light burner P. The heating oxygen valve V^o is opened sufficiently to produce a subatmospheric pressure in the chamber 39 at the end of the mixer nozzle 33 when the gas saver valves 29 and 45 are opened. The lever L is grasped by the fingers of the operator's hand which may be gripping the blowpipe handle H. The oxygen discharged through the mixer nozzle 33 draws the air and fuel gas from the chamber 39 around the nozzle. The three gases form a combustible mixture which is discharged at the end of the main nozzle N, where the mixture may be lighted by pressing the bypass valve thumb button 90 with the thumb of the operator's hand which may be gripping the handle H and the lever L. The heating flame having the characteristics for which the blowpipe may be designed is obtained by adjusting the heating oxygen valve only. The cutting oxygen valve knob C may be operated by the operator's thumb without changing the position of his grip on the handle H.

The modification disclosed in Fig. XIV is operated in a manner similar to that described in reference to Figs. I to XIII except that the oxygen valve V^o is first fully opened and the flame is adjusted by regulating the fuel gas valves V^a.

The constructions shown and described herein are illustrative of this invention but it will be understood that changes in the details as shown may be made without departing from the scope of the invention as defined in the appended claims.

We claim:

1. A blowpipe comprising passages for oxygen, and fuel gas; means for forming a combustible mixture containing each of said gases; and a single means adapted to be operated to control the admission of each of said gases to said mixture forming means; and means for admitting atmospheric air to one of said passages, said last-named means being so constructed as to prevent an outward flow of gases therethrough.

2. A blowpipe having inlets for air, oxygen and a fuel gas; a mixer adapted to form a combustible mixture containing each of said gases; said mixer having a throat and a chamber in rear of said throat; an injector nozzle extending into said chamber and having a passage therein adapted to discharge a gas into said throat and aspirate gas from said chamber; a valve for controlling the flow of gas through said passage; said mixer having a passage forming a communication be-

tween said chamber and said inlet for air; said mixer having another passage leading into said chamber; a valve for controlling the flow of gas through said latter passage; the inlet of one of said valves being connected to said inlet for oxygen and the inlet of the other valve being connected to said inlet for fuel gas; and a single means adapted to control the opening and closing of said valves.

10. 3. A blowpipe having inlets for air, oxygen and a fuel gas; a mixer adapted to form a combustible mixture containing each of said gases; said mixer having a throat and a chamber in rear of said throat; an injector nozzle extending into said chamber and having a passage therein adapted to discharge a gas into said throat and aspirate gas from said chamber; a valve for controlling the flow of gas through said passage; said mixer having a passage forming a communication between said chamber and said inlet for air; said mixer having another passage leading into said chamber; a metering plug in said latter passage having an orifice adapted to limit the flow of gas therethrough to maintain a subatmospheric pressure in said chamber; a valve for controlling the flow of gas through said latter passage; the inlet of one of said valves being connected to said inlet for oxygen and the inlet of the other valve being connected to said inlet for fuel gas; and a single means adapted to control the opening and closing of said valves.

4. A blowpipe having inlets for air, oxygen and a fuel gas; a mixer adapted to form a combustible mixture containing each of said gases; said mixer having a throat and a chamber in rear of said throat; an injector nozzle extending into said chamber and having a passage therein adapted to discharge a gas into said throat and aspirate gas from said chamber; a valve for controlling the flow of gas through said passage; said mixer having a passage forming a communication between said chamber and said inlet for air; said mixer having another passage leading into said chamber; a valve for controlling the flow of gas through said latter passage; a removable metering plug located in the outlet of said latter valve; said plug having an orifice therein adapted to limit the flow of gas from said latter valve so that a subatmospheric pressure may be maintained in said chamber; the inlet of one of said valves being connected to said inlet for oxygen and the inlet of the other valve being connected to said inlet for fuel gas; and a single means adapted to control the opening and closing of said valves.

55. 5. A blowpipe adapted to form a combustible mixture of air, oxygen and a fuel gas comprising an oxygen passage and a fuel gas passage; a mixer having a throat and a subatmospheric pressure chamber connected to said throat; a removable injector nozzle adapted to discharge one of said gases into said throat and produce a subatmospheric pressure in said chamber; said nozzle having a passage connecting said chamber with the atmosphere and having a passage communicating with the said oxygen passage upon insertion of the nozzle in place in the blowpipe; said mixer having a passage connecting a source of supply of another of said gases with said chamber; and each of said passages having a maximum predetermined fixed flow section.

70. 6. A blowpipe adapted to form a combustible mixture of air, oxygen and a fuel gas comprising a mixer having a throat and a subatmospheric pressure chamber connected to said throat; an injector nozzle adapted to discharge one of said

gases into said throat and produce a subatmospheric pressure in said chamber; said mixer having a passage connecting said chamber with the air surrounding the blowpipe; said air passage having a maximum predetermined fixed flow section; said mixer having a passage connecting a source of supply of another of said gases with said chamber; said latter passage having a removable plug therein; said plug having a metering orifice adapted to provide a fixed flow section for said passage.

7. A blowpipe comprising a mixer for forming a combustible mixture of air, oxygen and a fuel gas; a conduit for oxygen connected to a source of oxygen under pressure; a conduit for fuel gas connected to a source of fuel gas; a mixer throat; an injector nozzle having a passage therein connected to said conduit for oxygen and adapted to discharge oxygen into said mixer throat; a chamber connected to said mixer throat in rear of the discharge end of said injector nozzle; said chamber and said injector nozzle being so arranged that a subatmospheric pressure tends to be formed in said chamber upon the discharge of oxygen through said injector nozzle; an air conduit under atmospheric pressure connected to said chamber; a conduit for fuel gas connected to said chamber; a removable plug in said conduit for fuel gas; said plug having a passage therethrough to limit the flow of fuel gas to said chamber to assist in the maintenance of a subatmospheric pressure in said chamber and determine the ratio of air to fuel gas in the combustible mixture.

8. A blowpipe comprising a handle; a blowpipe head having a main nozzle attached thereto; a mixer for forming a combustible gas mixture; a conduit connecting the outlet from said mixer to said nozzle; a conduit connecting said mixer to a source of combustion supporting gas; a conduit connecting said mixer to a source of fuel gas; a normally closed valve in said conduit for the combustion supporting gas; a normally closed valve in said conduit for the fuel gas; and a common means for opening both of said valves; said means being operable to open said valve in said conduit for the combustion supporting gas before it opens said valve in said conduit for the fuel gas.

9. A blowpipe comprising a handle; a cutting oxygen valve carried by said handle; a valve stem in said handle having its longitudinal axis arranged parallel to the longitudinal axis of said handle; said stem being adapted to operate said valve; a plunger slidably supported in said handle and adapted to operate said stem; the longitudinal axis of said plunger being parallel to the longitudinal axis of said stem and being offset therefrom toward the longitudinal axis of said handle; a lever pivoted in said handle; said lever having an arm adapted to actuate said plunger; and said lever having a second arm extending at substantially a right angle to said first arm and adapted to be actuated from without said handle.

10. A blowpipe comprising a blowpipe nozzle; a gas mixer adapted to deliver combustible gas mixture to said nozzle; a conduit for supplying oxygen to said mixer; a conduit for supplying fuel gas to said mixer; and means for admitting air into one of said conduits, such air-admitting means being constructed so as to prevent a reverse flow of gas therethrough.

11. A blowpipe as claimed in claim 10, in which said means is constructed to admit air into such fuel gas supply conduit, while preventing gas discharge to the atmosphere.

12. A blowpipe comprising a blowpipe nozzle; a gas mixer adapted to deliver combustible gas to said nozzle; said mixer comprising a chamber and a mixer nozzle having a passage in communication with said chamber; a conduit for supplying fuel gas to said chamber; a conduit for supplying oxygen to said passage in the mixer nozzle; a conduit for admitting air into one of such gas supply conduits; and a check valve adapted to obstruct the outflow of gas through such air-admitting conduit. 5
13. A blowpipe comprising a blowpipe nozzle; a gas mixer adapted to deliver combustible gas to said nozzle, said mixer comprising a chamber and a mixer nozzle having two passages therein, both passages opening into said chamber; a conduit for supplying fuel gas to said chamber; a conduit for supplying oxygen to one of said passages in said mixer nozzle; and an automatically-operable check valve adapted to admit air into the other of said passages in said mixer nozzle but obstructing the outflow of gas through such other passage. 10
14. A blowpipe having in combination a body provided with a fuel gas passage and an oxygen passage therein; said oxygen passage leading to and discharging into the fuel gas passage; a removable metering orifice member in said fuel gas passage; a removable nozzle and air inlet member establishing communication between one of said passages and the atmosphere; and a housing member having an air intake passage therethrough and having means responsive to pressure 15

within the air inlet member for controlling air flowing through the latter; the said nozzle member also having therein an unobstructed oxygen passage in permanent communication with the first-named oxygen passage. 20

15. A blowpipe comprising a body portion having a counterbored chamber; means for conducting different gases to spaced points along said counterbored chamber; a nozzle within said counterbore provided with means at a point between said spaced points adapted to secure it therein and having reduced portions adjacent said securing means to form auxiliary chambers with said bore at said points; a conduit adapted to connect one of said auxiliary chambers with a central duct within said nozzle; and means for introducing a third gas to said other auxiliary chamber comprising passages extending substantially throughout the length of said nozzle. 25

16. A blowpipe as claimed in claim 15 wherein the central duct within said nozzle exits into said other auxiliary chamber at a point beyond the entrance thereto of said other gases. 30

17. A blowpipe as claimed in claim 15 wherein one of said auxiliary chambers is supplied with oxygen, acetylene is introduced to said other auxiliary chamber, and air is introduced to said last mentioned auxiliary chamber through passages extending substantially throughout the length of said nozzle. 35
